SPARK PLUG

Melville F. Peters, Beltsville, and Henry K. King,
Bethesda, Md.

Application April 19, 1940, Serial No. 330,546

10 Claims. (Cl. 123—169)

(Granted under the act of March 3, 1883, as
amended April 30, 1928; 370 O. G. 757)

This invention relates to an improved spark plug, and specifically to a spark plug having a plurality of gaps in series and a unique type of construction.

In order to operate successfully, a spark plug must combine certain thermal, electrical and mechanical characteristics. The spark must fire the fuel-air mixture without the temperature of any part of the plug becoming high enough to cause pre-ignition and without the electrical resistance becoming low enough to cause a shorting of the plug to ground. Reliable firing and long life is reasonably assured if a low temperature of the spark plug can be maintained.

It is an object of this invention to provide a spark plug utilizing the series gap principle and so constructed as to permit its use in modern high output engines.

It is a further object of this invention to provide a spark plug so constructed that the temperature over all portions of the plug will be maintained at a low temperature under severe operating conditions.

It is a still further object of this invention to provide a construction which will permit the use of smaller diameter plugs with a consequent increase in thermal efficiency, but with no loss in mechanical ruggedness and strength.

It is well known that in a laminated mica core construction the interspersing of metal washers between the mica washers provides an increased thermal conduction from the surface of the core in contact with the flames to the center shank which carries the heat away, but in such construction care has always been taken to prevent electrical flashover, due to the use of the metal washers, and the regular spark gap was provided elsewhere. It is also well known that a series of gaps between pins, rings, or other intermediate metallic paths, gives certain desirable electrical characteristics. However, such devices are subject to local overheating and cause pre-ignition in high output engines. The device of this invention successfully combines the advantages of both types and eliminates some of the electrical disadvantages of the parallel gap type while eliminating the thermal disadvantages of the series gap type.

Referring now to the drawing:

Fig. 1 is a cross-sectional view of one embodiment of the improved spark plug of this invention, taken along its longitudinal axis.

Fig. 2 is an enlarged view of a fragment of Fig. 1, showing the details of the lower end of the spark plug.

Fig. 3 is a view similar to Fig. 1, showing a second embodiment of the invention; and

Fig. 4 is an enlarged view of a fragment of Fig. 3, showing the details of the lower end of the plug.

Referring now to the embodiment shown in Fig. 1, the plug is built up around the central spindle shank 1, extending longitudinally thereof. A mica cigarette 2 surrounds the spindle shank 10 throughout its length and protrudes for a certain distance below its lower end. A metal shell 3 contains the spark plug assembly. The upper portion of this shell is thin walled and spaced from the central spindle shank. The power portion 4, however, is thickened to form a snug fit about the mica cigarette 2. The thickening takes place at a shoulder 5 above which an outer mica cigarette 6 fits snugly against the inside wall of the shell.

20 It will be noted that the top of spindle shank 1 terminates a considerable distance below the top of the shell. This space may be filled with a pile of mica washers, the upper end 8 of the shell 3 being spun over to maintain them in place.

25 The space between the inner cigarette 2 and the outer cigarette 6 is filled with a pile of mica washers 21, the upper end of the spindle shank 1 being flanged outwardly at 9. The mica washers 7 may be omitted, if desired. The thickened portion 4 of the shell is screw threaded to fit the standard threaded hole in the engine cylinder.

30 The lower end of the shell is partially closed by a member 10 having a hole extending through its center. Between the lower end of the spindle shank 1 and the member 10 is located an assembly of washers forming a series of spark gaps. The assembly consists of a series of mica washers 11, between which are interspersed a series of metal washers 12. It will be noted that the

35 central hole through each of the mica washers is of a larger diameter than that through the metal washers, thus providing a series of air gaps bridging the distance between the lower end of the spindle shank and the member 10, across each of which sparking will occur.

The mica washers fit snugly against the cigarette 6. However, the outer diameter of the metal washers is small enough that a considerable annular gap is left between each metal washer 50 and the cigarette 6. Into this space an insulating compound 13 is placed. The lower outer corner of each metal washer is rounded at 14 to increase the distance between this portion of the washer and the upper corner of the adjacent washer, and to decrease the electrical gradients.

at this edge, thus preventing the occurrence of any sparking at this point. The upper outer corner of each metal washer is smoothed off and slightly rounded, so that the upper surface of the washer is flat so as to provide the maximum amount of bearing surface for the superimposed mica washer, thus preventing breakage of the mica washer.

In the second embodiment of the invention shown in Figs. 3 and 4, the central spindle shank 1 extends below the lower end of the shell and terminates at its lower end with a strong outwardly turned flange 15. The upper portion of the plug assembly is constructed in the same manner as previously described. The lower portion, however, is somewhat different. In this embodiment the series of spark gaps is provided by means of an assemblage of metal washers 16, between which are interpersed mica washers 17. The inner cigarette 2 extends the full length of the spindle shank 1, passing between the assemblage of the washers and the spindle shank. The general characteristics of the washers are the same as those used in the embodiment of Figs. 1 and 2, with the exception that the spark gaps are formed between the outer edges of the metal washers rather than the inner, and the configuration found in the outer portions of the metal washers of the previous embodiment is here found in the inner portions of the washers. The outer diameter of the metal washers in this embodiment is larger than that of the corresponding mica washers. The mica washers fit snugly against the inner cigarette 2, whereas the central hole through each of the metal washers is large enough to leave a central annular space between the cigarette and the metal washer, which space is filled with insulating compound 13, as in the previous embodiment. The lower inner edge 18 of each metal washer is rounded off in the same manner as was the lower outer edge 14 in the previous embodiment.

The upper metal washer of the series fits snugly against the metal of the shell to provide a good grounding connection.

Fitting snugly down upon the assemblage of washers is a conical member 19 which fits with a driving fit around the inner cigarette 2. The member 19 fits into a correspondingly shaped recess formed within the lower portion 4 of the shell.

If desired, the pile of mica washers 17 may be omitted as well as the upper portion of the shell, the shell being reduced in this case to the lower part 4, which merely acts as a bushing and a means of connecting the plug to the cylinder wall 20.

The metal washers must resist the temperatures and gases in the engine, but they should also possess sufficiently good heat conductivity and have such a coefficient of expansion that upon heating of the spark plug good thermal contact will be maintained along the directions shown by the arrows in Fig. 4. In other words, the metal washers should have a coefficient of expansion relative to that of the surrounding materials, such that upon heating of the plug they will not become loose in the assembly.

While the disclosure has been restricted to two embodiments, the invention is to be considered as limited only by the scope and limitations of the appended claims.

The invention described herein may be manufactured and/or used by or for the Government of the United States of America for governmental

purposes without the payment of any royalties thereon or therefor.

We claim:

1. A spark plug assembly comprising a central spindle shank, a mica sheath completely enclosing the side walls of said shank, an outwardly flanged head formed on the lower end of said shank, a plurality of ring shaped terminals carried by the lower part of said shank, a plurality of insulating disks separating said terminals and spacing them to form spark gaps between each pair of adjacent terminals, a cone-shaped metal bushing fitted snugly around said mica sheath and against the upper one of said terminals, a metal bushing fitting snugly over said cone-shaped bushing and threaded for connecting said assembly to the cylinder wall of an engine, a column of mica washers fitted snugly around said sheath and down upon the upper surface of said outer bushing and means binding all the above mentioned elements into a compact unit.

2. A spark plug assembly comprising a central

spindle shank, a mica sheath completely enclos-

ing the side walls of said shank, an outwardly

flanged head formed on the lower end of said

shank, a plurality of ring shaped terminals car-

ried by the lower part of said shank, a plurality

of insulating disks separating said terminals and

spacing them to form spark gaps between each

pair of adjacent terminals, a cone-shaped metal

bushing fitted snugly around said mica sheath

and against the upper one of said terminals,

a metal bushing fitting snugly over said cone-

shaped bushing and threaded for connecting said

assembly to the cylinder wall of an engine, a col-

umn of mica washers fitted snugly around said

sheath and down upon the upper surface of said

outer bushing, and an outwardly turned flange

formed upon the upper end of said shank and

binding all the above mentioned elements into

a compact unit.

3. A spark plug assembly comprising a cylin-

drical shell, a central spindle shank extending

longitudinally of said shell and terminating short

of the lower end thereof, an insulating sheath

enclosing the side walls of said shank, a plu-

rality of ring-shaped terminals contained in the

lower end of said shell and beneath said shank,

a plurality of ring-shaped insulating disks inter-

spersed between said terminals, said disks having

larger central holes than said terminals and serv-

ing to space said terminals apart so that spark

gaps are formed between the adjacent edges of

the central holes of adjacent terminals, and

means insulating said terminals from said shell.

4. In a spark plug, a terminal assembly com-

prising a plurality of ring-shaped metal terminals

of generally rectangular cross section, a plurality

of ring-shaped elements of insulating material,

each separating a pair of said terminals by a

distance sufficient to create an efficient spark

gap between them, the diameter of the hole in

each of the ring shaped elements being larger

than that of each of the ring-shaped terminals,

whereby an air-gap will be formed between the

central portion of adjacent terminals, an insu-

lating sheath surrounding said terminals and ele-

ments and annularly spaced from said terminals,

at least one of each pair of adjacent outer edges

of each adjacent pair of terminals being rounded

off and insulating material filling said annular

space and means binding said assembly together

into a compact unit.

5. In a spark plug, a terminal assembly com-

prising a plurality of ring-shaped metal terminals

of generally rectangular cross section, a plurality of ring-shaped elements of insulating material, each separating a pair of said terminals by a distance sufficient to create an efficient spark gap between them, the outer diameter of each of said terminals being greater than that of said ring-shaped elements, whereby an air-gap will be formed between the peripheral portions of adjacent terminals, means passing through each of said elements and terminals and binding the whole assembly into a compact unit, the inner diameter of each of said terminals being sufficient to leave an annular space between it and said binding means, at least one of each pair of adjacent inner edges of each adjacent pair of terminals being rounded off and insulating material filling each of said spaces.

6. In a spark plug, an outer shell having a partially closed bottom formed with a central aperture, a lining of insulating material on the inside of said shell, a terminal assembly carried therein, said assembly comprising a plurality of ring-shaped metal terminals, a plurality of ring-shaped elements of insulating material, each separating a pair of said terminals by a distance sufficient to create an efficient spark gap between them, the diameter of the hole in each of the ring-shaped elements being larger than that of each of the ring-shaped terminals, whereby an air-gap will be formed between the central portions of adjacent terminals, the outer diameter of each of said ring-shaped terminals being such as to leave an annular space between said terminal and said lining, the lower outer edge of each of said terminals being rounded off, an insulating substance filling said annular space and means holding said terminals and said elements into a compact unit.

7. In a spark plug, a central spindle shank, a terminal assembly comprising a plurality of ring-shaped terminals, a plurality of ring-shaped elements of insulating material, each separating a pair of said terminals by a distance sufficient to create an efficient spark gap between them, the outer diameter of each of said terminals being greater than that of said ring-shaped elements, whereby an air-gap will be formed between the peripheral portions of adjacent terminals, said spindle shank being inserted through all said

5 terminals and elements, a sheath of insulating material interspersed between said spindle shank and said terminals and elements, the diameter of the hole in each of said terminals being such as to leave an annular space between said sheath and said terminal, the lower inner edge of each of said terminals being rounded off, an insulating substance filling said annular space, and means comprising means on said spindle shank holding said terminals and said elements into a compact unit.

8. A spark plug terminal, comprising a metal annulus having a cross-section presenting two angular outer corners and at least one rounded inner corner, said cross-section being so shaped that when a plurality of said terminals are stacked and separated from each other by wafers of insulation, the distance between the adjacent outer corners of adjacent terminals will be at least as short as the distance between any two adjacent points on said adjacent terminals.

9. A spark plug terminal, comprising a metal annulus having a cross-section presenting two angular inner corners and at least one rounded outer corner, said cross-section being so shaped that when a plurality of said terminals are stacked and separated from each other by wafers of insulation, the distance between the adjacent inner corners of adjacent terminals will be at least as short as the distance between any two adjacent points on said adjacent terminals.

10. A spark plug assembly comprising a central spindle shank, a mica sheath completely enclosing the side walls of said shank, an outwardly flanged head formed on the lower end of said shank, a plurality of ring-shaped terminals carried by the lower part of said shank, a plurality of insulating disks separating said terminals and spacing them to form spark gaps between each pair of adjacent terminals, a cone-shaped metal bushing fitted snugly around said mica sheath above said terminals, a metal bushing fitting snugly over said cone-shaped bushing, a column of insulation fitted snugly around said sheath and down upon the upper surface of said outer bushing and means binding all the above mentioned elements into a compact unit.
